UNITED STATES PATENT OFFICE

HARRY NEGBAUR, OF NEW YORK, N. Y., ASSIGNOR TO H. NEGBAUR & CO., INC.,
A CORPORATION OF NEW YORK

DESIGN FOR A DISH OR ARTICLE OF ANALOGOUS NATURE

Application filed February 13, 1933. Serial No. 47,208. Term of patent 3½ years.

To all whom it may concern:

Be it known that I, HARRY NEGBAUR, a citizen of the United States of America, and a resident of New York, in the county of New York and State of New York, have invented a new, original, and ornamental Design for a Dish or Article of Analogous Nature, of which the following is a specification, reference being had to the accompanying drawing, forming a part hereof. In the drawing:

Fig. 1 is a side elevational view of the dish

or article of analogous nature, showing my new design;

Fig. 2 is an inverted plan view of the dish or article of analogous nature, the feet or legs shown in Fig. 1 being omitted for the sake of clearness; and

Figs. 3 and 4 are elevational views of the ornamental panels on the side opposite Fig. 1.

I claim:

The ornamental design for a dish or article of analogous nature as shown and described.

HARRY NEGBAUR.
